BACKGAMMON GAME BOARD

Ulysses Othon, Jackson Heights, N. Y.

Application December 1, 1949, Serial No. 6,368

Term of patent 14 years

(Cl. D34—5)

To all whom it may concern:

Be it known that I, Ulysses Othon, a citizen of the United States, residing at Jackson Heights in the city of New York, State of New York, have invented a new, original, and ornamental Design for a Backgammon Game Board, of which the following is a specification, reference being had to the accompanying drawing, forming a part hereof.

Fig. 1 is a top plan view of the backgammon game board, showing my new design; and

Fig. 2 is a cross-sectional elevational view thereof taken on line 2—2 in Fig. 1.

The sides and bottom of the game board are plain and unornamented.

I claim:

The ornamental design for a backgammon game board, as shown and described.

ULYSSES OTHON.
